UNITED STATES PATENT OFFICE.

WILLIAM E. PEARSON, OF SWAMPSCOTT, MASSACHUSETTS.

REVERSIBLE-EXPLOSIVE-ROTARY-ENGINE UNIT.

No. 901,554.

Specification of Letters Patent.

Patented Oct. 20, 1908.

Application filed December 4, 1907. Serial No. 405,108.

To all whom it may concern:

Be it known that I, WILLIAM E. PEARSON, a citizen of the United States, of Swampscott, in the county of Essex and State of Massachusetts, have invented a new and useful Improvement in Reversible-Explosive-Rotary-Engine Units, of which the following, taken in connection with the accompanying drawings, is a specification.

My invention relates to that class of explosive rotary engines in which compressed mixtures of air and gases or vapors are used for generating power; and consists in the construction and arrangement of parts, and may be best understood by reference to the full description.

The object of the invention is to so construct and arrange the parts that the whole shall constitute a unit for developing power, all the elements of the engine having continuous rotary movements, and are so constructed that by the movement of a hand lever the engine will reverse its rotation. This object I attain by the mechanism illustrated in the accompanying drawings, in which

Figure 1 is a front elevation of my machine; Fig. 2 is an end elevation of the engine proper, viewed from line 2—2 of Fig. 1, made on a larger scale than Fig. 1. Fig. 1^a shows an end elevation of a part of the compressor with the carburettor attached. Fig. 3 is a vertical cross section taken through the casing of the engine but showing the piston carrier, pistons, the buttress and the valves in end elevation. Fig. 4 is a section of the engine and one of the rotating valves taken on line 4—4 of Fig. 3. Fig. 4^a shows the outer edge of one of the pistons, that is the part that bears on the interior surface of the cylinder. Fig. 5 is an end view of a part of the engine casing showing an adjustable bearing for the journal of the buttress. Fig. 6 is a horizontal section taken on line 6—6 of Fig. 3.

In the drawings the base of the entire machine is represented by A, Fig. 1, and is supported upon legs, A¹, A². The standard A² supports one end of the main shaft B³ of the engine proper B. The engine is secured to the base A, as shown.

Referring particularly to Figs. 3 and 6, the construction of the engine proper will be explained. The cylindrical casing is indicated by B, and the ends by B¹, B². C is the piston carrier and is mounted upon the main shaft

B³. The said piston carrier C has at its ends packing rings C⁴ C⁴ which are forced outward against the interior of the casing B¹ and B², by springs C⁵, C⁵. The packing rings have 60 radial arms, C⁶, C⁶, one of which is shown in full lines in Fig. 4 and two of them are shown in end view in Fig. 4^a. These radial arms C⁶, C⁶, pass through grooves made in the end of the pistons C⁷, as shown in Figs. 4 and 65 4^a, and act as packings for the ends of the said pistons. The said pistons C⁷, C⁷, of which there are two, are shown in end view in Fig. 3, and are forced outward with springs C⁸, thus insuring a close fit and providing for wearing.

The buttress, D, is mounted upon the shaft D¹, and has a piston-receiving recess d¹. This buttress makes two rotations for one rotation of the piston carrier C, and is connected by gearing, see Figs. 2 and 6, to the piston carrier. The said gearing consists of a large spur gear B⁴ which engages with a gear wheel D⁴ of one-half the diameter, on the shaft D³. The said shaft is mounted in adjustable housings D⁷ which have springs D⁸, and adjusting screws D⁹. The rotating buttress D has packing rings D⁶, D⁶, at its ends which are kept in contact with the inside of the casing by spiral springs D⁶—D⁶. 85

My engine is reversible and has one exhaust port, E, but requires two inlet ports, K and K¹, which are controlled by rotating valves; the construction of the said valves is shown in Figs. 3 and 4. Each inlet port is 90 controlled by a rotating valve H¹, which is mounted upon a shaft H², and is rotated by a spur gear H⁴, on the shaft of the said rotating valve. One of these rotating valves is shown in section in Fig. 4. The charge is 95 supplied to the rotating valve by the pipe H⁶, which is interiorly connected with the openings H⁵ through which the charge flows into the center chamber of the valve and from it is discharged through the openings H² (when 100 the valve is in position) into the piston chamber N or N¹, that is, into the chamber N to cause the pistons to move in one direction, that of the arrow, into the chamber N¹ to cause them to move in the other direction, 105 that is, the reverse.

I will now describe the compressor and its connection, see Fig. 1. The compressor consists of a pump, L, of the rotary class and is so constructed that it will work equally well 110 when running in either direction, that is, it is a reversible rotary pump, adapted to furnish

an explosive mixture as a charge for the rotary engine proper. The exploding charge is drawn from the carbureter R, through the pipe L¹ into the compressor pump L; from 5 the pump the charge is forced through the pipe L² to the mixer L³. This agitator or mixer consists of a casing L³ of any suitable dimensions and has within it a shaft L⁴ having propeller-like wings L⁵—L⁵ which rapidly 10 rotate and thus keep the charge mixed. To increase the efficiency of this device, I place within the outer casing L³ an inner casing L⁸, arranged as shown, leaving a passage 15 between the inner and outer casings and free passage at each end so that irrespective 20 of the way that the fans L⁵—L⁵ rotate there will be strong currents and eddy currents in the mixer casing or tank. This is essential 25 as the charge is often but a mixture of air and vapor and sometimes air and a sprayed fluid or air and a fixed gas of a different gravity or density. It will be seen 30 that this construction will maintain a homogeneous condition of the charge or mixture 35 whether the engine turns in one direction or the other. The mixing fans are driven by the main wheel B⁶ acting through the adjustable friction pulley L⁷ and the pulley L⁸. From the mixer L³ L⁸ the charge 40 passes through the pipe N⁷, N⁸, to the three-way cock N², thence through the pipe N⁴ to 45 the lower rotating valve H¹, see Fig. 3, or through the pipe N⁵, N⁶, to the upper rotating valve, also indicated by the letter H¹. In the latter case the charge passes through 50 the port K and causes the engine to operate as indicated by the arrow, Fig. 3. And in the other case the charge passes through the port K¹, and the engine is reversed. The three-way cock N² is operated by the hand lever N³, see Fig. 1. To prevent a too great 55 pressure in the mixer L³ L⁸, a pipe P leads to another and very important feature of my 60 engine is the clearance port, of which there are two, T and T¹, Fig. 3, located near the spark plugs S and S¹. The object of these 65 clearance ports is to allow of the escape of air and gases that may remain in the piston chamber after the piston has passed the exhaust port E; for instance, referring to Fig. 3 we see that the piston C⁵ has passed the exhaust port E, and that the chamber N¹ must 70 of necessity be filled with air taken in at the port E, or with the products of combustion remaining in the said chamber, after the explosion, and that had not been driven out before the piston C⁵ passed the exhaust port, it is evident that unless the said dead contents of the chamber N¹ is allowed to escape it will check, by becoming condensed, the rotation 75 of the piston carrier or it will pass by the buttress D¹ and expanding fill the chamber between the buttress D¹ and the piston C⁵, and

thus prevent a full explosive charge from entering through the valve K, the clearance port T being closed. Another advantage of having the piston chamber freed from air or other dead charge is that when the new 70 charge is admitted it is not diluted, and hence lowered in its efficiency, by the said air or other dead charge. It being understood that when the engine is running direct, that is, in the direction of the arrow, the clearance 75 port T is always closed, and when the engine is reversed the clearance port T¹ is always closed.

The means for opening and closing the clearance ports may be described as follows: 80 Attached to the hand reversing lever N³, Fig. 1, that operates the three-way cock N², is a short arm M¹, which is connected by the link M² to a short arm M² which operates the valve of the clearance port T¹. The same link M³ 85 is also connected by a second link M⁴ to a short lever M which operates the valve of the clearance port T.

From the above it may be seen that the lever which controls the explosive charge and 90 sends it to the direct charge port K or to the reverse charge port K¹, also controls the clearance ports T and T¹, always closing one when opening the other.

Claims.

95

1. An explosive rotary engine unit, comprising a casing, having exhaust and inlet ports; a cylindrical continuously rotating piston carrier and pistons; a continuously rotating buttress; continuously rotating 100 valves controlling and directing the charges; a continuously rotating charge compressor, a charge reservoir having rotating mixers, and means for operatively connecting the several parts; substantially as and for the purpose set forth.

105

2. A reversible explosive rotary engine unit, comprising a casing, having exhaust and inlet ports; a cylindrical continuously rotating piston carrier and pistons; a continuously rotating buttress; continuously rotating 110 valves controlling and directing the explosive charges; a continuously rotating charge compressor; a charge reservoir; an exhaust port and clearance ports and means 115 for operatively connecting the several parts; substantially as and for the purpose set forth.

115

3. A reversible explosive rotary engine unit comprising a casing having exhaust and inlet ports; a cylindrical continuously rotating piston carrier and pistons; continuously rotating valves controlling and directing the charges; a continuously rotating charge compressor; a charge reservoir having continuously rotating mixers; clearance ports and 120 means for operatively connecting the several parts; substantially as and for the purpose set forth.

120

4. In a rotary engine apparatus, a reversing valve, a lever for operating the said valve, 130

clearance ports having closing valves and mechanism connecting said reversing valves with the closing valves of the said clearance valves whereby the said reversing valves and the said clearance valves will be operated substantially as and for the purpose set forth.

In testimony whereof, I have signed my

name to this specification in the presence of two subscribing witnesses, on this 3d day of December A. D. 1907.

WILLIAM E. PEARSON.
